UNITED STATES PATENT OFFICE.

CHARLES H. NOWACK, OF OAK PARK, ILLINOIS, ASSIGNOR TO AMERICAN CAN COMPANY, OF NEW YORK, N. Y., A CORPORATION OF NEW JERSEY.

POURING-SPOUT.

1,340,242.

Specification of Letters Patent. Patented May 18, 1920.

Application filed March 3, 1916. Serial No. 81,780.

To all whom it may concern:

Be it known that I, CHARLES H. NOWACK, residing in Oak Park, in the county of Cook and State of Illinois, have invented a new 5 and useful Improvement in Pouring-Spouts, of which the following is a specification.

This invention relates in general to pouring spouts and has more particular reference to pouring spouts provided for use in 10 connection with the packaging of various liquids.

A principal object of the invention is the provision of an efficient pouring spout which may be provided for use on containers or cans having a nozzle about which the 15 spout may be fixed either by the packer or user. It will however be understood that the invention has other advantages which render it capable of effective and efficient 20 use when it forms a permanent part of the nozzle itself.

A further object of this invention is the provision of a spout which, when positioned upon a container, will permit fracturing of 25 a seal located within a nozzle or a nozzle part of the spout and which will be normally covered or closed except for the presence of the ordinary spout or pouring orifice.

30 A further object of the invention is the provision of a spout which may be positioned upon a nozzle and which will insure a smooth pouring action without any danger of leakage through the connection between the spout and nozzle.

35 Other objects and advantages of the invention will be apparent as it is better understood from the following description when considered in connection with the accompanying drawings illustrating a preferred embodiment thereof.

On the drawings,

40 Figure 1 is a perspective view of a container provided with a spout embodying my invention;

Fig. 2 is a vertical section through the same;

Fig. 3 is a section taken substantially on the line 3—3 of Fig. 2;

45 Fig. 4 is a front elevation of said spout separated from the nozzle to which it is to be attached; and

Fig. 5 is a perspective view of the main part of the spout.

50 For the purpose of illustrating my inven-

tion I have shown on the drawing a container A having a nozzle B upon which is positioned a spout C embodying my present invention.

Referring to Figs. 1 and 2 it will be noted 60 that the container comprises a body 6 of any preferred construction having a nozzle opening 7 in its upper face in which is secured the nozzle B by a seam 8 of any desired form. The nozzle B in the present instance is of cylindrical form and is provided just beneath its top with an inwardly extending collapsed bead 9 upon which seats a frangible seal or closure 10, which seal or closure is held in place by the upper edge 65 11 (Fig. 2) of the nozzle which is curled over upon it for this purpose.

The spout embodying my present invention consists of two parts 12 and 13, the part 12 being the body or lower or main 75 part of the spout and the part 13 being what may be termed a sliding slip cover which constitutes the upper part. The part 12 comprises, in the present instance, a body 14 of cylindrical form cut away at its front 80 opposite the spout proper. This partially cylindrical part 14 is adapted to embrace the outer face of the nozzle and carries a reinforcing bead 15 at its bottom. A lip 16 formed on a slightly smaller radius than the 85 cylindrical part 14, extends into the opening at the front of the body, and this lip is curled upwardly and arcuately at 17 to embrace the curled edge 11 of the nozzle. The free edge of the lip extends downwardly within the nozzle in tight metal to metal engagement with the curled edge to prevent leakage of the contents in pouring. The lower part of the spout proper extends 90 outwardly from the bend 17 and tapers to a 95 small semi-circular opening or end 18. The edges 19 of the spout proper slope downwardly toward the rear.

The upper part or sliding slip cover 13 consists of a sheet of metal of general superficial form approximating the opening into the lower part 12 of the spout. Its edges are bent to engage about and beneath the edges 19 of the lower part of the spout and they continue rearwardly in the form of 100 a flange 21 adapted to slip down over the back end of the spout body. This cover may be positioned by engaging the forward corners 22 beneath the spout end and sliding them back until the flange 21 may be 105 110

lowered about the rear side and it may be removed by reversing these steps.

The body of the spout is provided with depressions 23 adapted to engage in the bead 9 to aid in holding the spout in place, the parts being so constructed that these depressions spring into the recess in the collapsed bead 9 when the spout has been forced downwardly a proper distance.

10 The entire spout is detachable and can be furnished upon the package or as an article for subsequent attachment, as desired. Also the spout may be turned around on the nozzle so as not to project beyond the sides of 15 the can, the depressions 23 sliding in the bead 9 as the spout is turned.

It is thought that the invention and many of its attendant advantages will be understood from the foregoing description, and 20 it will be apparent that various changes may be made in the form, construction and arrangement of the parts without departing from the spirit and scope of the invention or sacrificing any of its material advantages, 25 the form hereinbefore described being merely a preferred embodiment thereof.

I claim:—

1. A pouring spout adapted for attachment to a nozzle and having a body for 30 embracing said nozzle, and a lip insertible within the nozzle at the spout side of said body.

2. A pouring spout adapted for attachment to a nozzle and having a part disposed 35 within the nozzle and engaging the inner side of the same and a depending neck disposed about said nozzle and parallel with said part which is disposed within the nozzle.

40 3. A pouring spout having a body open at its top and extending at one side to form the under part of the spout and a sliding slip cover having its edges bent to embrace the lower spout part under the same and being 45 flanged to engage about the body opposite said spout part, said slip cover being held from longitudinal movement by said bent edges and flange, and being slidable and removable when its flanged part has been 50 lifted.

4. A pouring spout adapted for attachment to a nozzle, formed with a lateral spout portion, a depending flange adapted to embrace the exterior of such nozzle, and a 55 depending lip arranged at the inner end of the lateral spout portion and adapted to be inserted within such nozzle.

5. The combination of a nozzle, a remov-

able pouring spout having a flange at its rear part which engages the exterior of the 60 nozzle at one side and is cut away at the other side of the nozzle, and having a lip at the front part of the nozzle in line with the pouring extension of the spout and engaging within the nozzle.

6. The combination of a nozzle and a pouring spout, said spout having a curved vertical flange which engages the nozzle exteriorly and a lip which engages the nozzle 70 interiorly.

7. The combination of a nozzle having a depression on its exterior, and a removable spout having a yieldable cylindrical flange which engages the periphery of the nozzle, a portion of said flange being cut away, said 75 flange having an inward projection adapted to snap into said depression of the nozzle and to be held removable therein by said yieldable flange.

8. A combined nozzle and pouring spout, 80 the spout portion extending laterally from the upper part of the device, a frangible seal fixed in the nozzle portion of the device accessible through the top of the nozzle and spout portions when the latter are open, and 85 a nozzle and spout cover having flanges at its pouring extremity which externally and slidably engage around and under said spout portion and having a vertical flange at its rear end which slidably engages the 90 exterior of said nozzle portion after the cover has been engaged under the spout portion and slid rearwardly, said cover being removable to give direct access to the top of said frangible seal, and said spout 95 being removably attachable to the nozzle.

9. A combined nozzle and pouring spout, the spout portion extending laterally from the upper part of the nozzle portion, and a removable nozzle and spout cover having 100 flanges at its pouring extremity which externally and slidably engage around and under said spout portion and having a vertical flange at its rear end which slidably engages the exterior of said nozzle portion 105 after the cover has been engaged under the spout portion and slid rearwardly, said spout being removably attachable to the nozzle.

Signed in the presence of two subscribing 110 witnesses.

CHARLES H. NOWACK.
